By G. N. Hammett Atty.*

UNITED STATES PATENT OFFICE.

PAUL F. TITCHENER, OF BINGHAMTON, NEW YORK.

DESIGN FOR A BATHROOM APPLIANCE.

Application filed February 2, 1925. Serial No. 12,241. Term of patent 3½ years.

To all whom it may concern:

Be it known that I, PAUL F. TITCHENER, a citizen of the United States, residing at Binghamton, in the county of Broome and State of New York, have invented a new, original, and ornamental Design for Bathroom Appliances, of which the following is a specification, reference being had to the accompanying drawing, forming a part thereof, which is a perspective view.

I claim:

The ornamental design for a bathroom appliance, as shown.

In testimony whereof I affix my signature.

PAUL F. TITCHENER.
